US00D500323S

(12) **United States Design Patent** (10) Patent No.: **US D500,323 S**
(45) Date of Patent: **** Dec. 28, 2004**

(54) **AUDIO VIDEO SELECTOR COMPONENT**

(75) Inventors: **Saied Hussaini**, Miami, FL (US); **Marc Iacovelli**, Miami, FL (US)

(73) Assignee: **Intec, Inc.**, Miami, FL (US)

(**) Term: **14 Years**

(21) Appl. No.: **29/193,066**

(22) Filed: **Nov. 4, 2003**

(51) LOC (7) Cl. **14-03**

(52) U.S. Cl. **D14/496**

(58) Field of Search **D14/496, 125, D14/217, 299, 400, 401; D21/324, 328, 332, 333; 340/825.25, 825, 825.23; 273/148 B; 463/1, 46, 47, 43; 381/73.1; 345/156, 157, 905, 906**

(57) **CLAIM**

The ornamental design for an audio video selector component, as shown and described.

DESCRIPTION

FIG. 1 is a top view of the audio video selector component according to the present invention.

FIG. 2 is a bottom view of the audio video selector component of FIG. 1.

FIG. 3 is a front view of the audio video selector component of FIG. 1.

FIG. 4 is a back view of the audio video selector component of FIG. 1.

FIG. 5 is a right side view of the audio video selector component of FIG. 1.

FIG. 6 is a left side view of the audio video selector component of FIG. 1; and,

FIG. 7 is a left and top perspective view of the audio video selector component of FIG. 1.

The broken lines are for illustrative purpose and form no part of the claimed design.
